SKI ATTACHMENT FOR WHEELED VEHICLES

"E" Lee Rae Clark, Spokane, Wash.

Application October 17, 1949, Serial No. 121,760

3 Claims. (Cl. 280—13)

1

This invention relates to a ski attachment for castors or wheels of the type used upon vehicles such as perambulators used for infants and it is one object of the invention to provide a ski attachment which may be applied to the castors or other wheels of the vehicle and thus allow use of the vehicle when streets and sidewalks are covered with snow or ice.

Another object of the invention is to provide an attachment of this character wherein skis are 10 individually applied to the vehicle wheels and thus allow them to be conveniently applied and secured.

Another object of the invention is to provide skis which are provided with sockets into which the vehicle wheels fit, each socket being equipped with a clamp of simple construction and by means of which the wheel will be firmly secured in the socket.

Another object of the invention is to provide skis of such construction that a pair of skis may be connected in transverse spaced relation and prevented from moving out of desired spaced relation to each other.

With these and other objects in view the invention consists of a special construction and arrangement of parts, one practical embodiment of which is illustrated in the accompanying drawings wherein:

Fig. 1 is a perspective view showing a pair of skis of the improved construction connected in transverse spaced relation to each other.

Fig. 2 is a view upon an enlarged scale showing the improved ski in longitudinal vertical section.

The conveyance to which the improved ski is intended to be applied may be of any type having wheels but in the illustration it has been shown applied to a wheel 1 of a castor 2 and since the vehicle has such castors at opposite sides of the vehicle there have been shown two of the skis in Figure 1, the skis being held in transverse spaced relation to each other such a distance that the wheels of the two castors may fit into sockets of the companion skis.

The skis 3 are of duplicate construction and each consists of a thin strip of suitable length and width which has its front end portion 4 turned upwardly in the usual manner. A bead 5 extends along the under face of the ski midway the width thereof for the full length of the ski. A socket 6 is mounted upon the upper face of the ski midway its length and is open at its top so that the wheel 1 may be thrust downwardly into the socket and fit snugly therein, as shown in Figure 2. The socket is formed of sheet metal

2

and has inner and outer side walls 7 and 8 and front and rear end walls 9 and 10, lower portions of these walls being cut and bent to form attaching flanges or feet 11 which are firmly secured in flat face to face engagement with the upper face of the ski. Upper end portions of the side walls are formed with recesses 12 and 13 which are cut along arcuate lines and are of such dimensions that portions of the hub of the wheel projecting from opposite sides thereof may fit into the recesses and assume a position in centered relation thereto. By so forming the recesses they have cam surfaces along their edges and when the wheel is thrust downwardly into the socket the hub will engage the curved edges of the recesses and thus guided to a position in which the wheel is properly seated in the socket in case the wheel has a tendency to move too far forwardly or rearwardly as it is forced downwardly into place. A tongue 14 is cut from the inner side wall of each socket in front of the recess 12 and this tongue is bent downwardly so that it projects laterally from the socket. This tongue or ear 14 is formed with an opening and skis applied to opposed wheels of a vehicle may be connected by a brace 15 consisting of rods 16 and a turn buckle 17.

The rods have their outer ends formed with eyes 18 which rest upon the ears 14 and bolts 19 are passed through the eyes and the ears and tightened to pivotally secure the rods to the ears. The skis will thus be secured together to cause any transverse movement of one ski to be transmitted to the other and thus maintain the skis in parallel spaced relation. When the turnbuckle is rotated transverse adjustment may be made to align the skis.

When the wheels are thrust downwardly into the sockets they should be held against upward movement out of the sockets. In order to do so each socket is provided with a clamp 20. The clamps are resilient and each formed from a strip of sheet metal which is bent to form a flat foot 21 and upwardly projecting arms 22 and 23. The arm 22 is straight throughout its length and when the clamp is fitted into the socket with its foot resting upon the portion of the ski forming the bottom of the socket the arm 22 will have flat contacting engagement with the rear wall of the socket for the full depth of the socket. The arm 23 is curved longitudinally so that it may fit about the periphery of the wheel and is of such length that its upper end portion projects upwardly from the socket. The upper end portions of the rear wall and the arm 22 are bored to form an open-

ing 24 and against the outer face of the rear end wall is mounted a nut 25 which registers with the opening 24. Therefore a thumb screw 26 may be threaded through the nut and the opening and have its inner end portion project from the arm 22 and its end disposed in abutting engagement with the upper portion of the arm 23. When the thumb screw is loosened the arm 23 will have sufficient give to allow the wheel to be thrust downwardly into the socket where it rests upon the bottom of the socket. After the wheel has been thrust into the socket the thumb screw is tightened and it will force the resilient arm 23 towards the wheel and hold the arm in such frictional gripping engagement with the wheel that the wheel can not slip out of the socket. The ski will thus be firmly held to the wheel to which it is applied but may be easily removed when so desired by loosening the screw and withdrawing the wheel from the socket. When a ski of the improved construction is applied to a single wheel at the front of a vehicle the rod 16 is detached from its ear 14, or if so desired skis which are intended to be used upon a single front or rear wheel of a vehicle may have the ear 14 omitted.

Having thus described the invention, what is claimed is:

1. An attachment for a wheeled vehicle comprising a ski, a wheel-receiving socket carried by and projecting upwardly from said ski and open at its top and having side walls and front and rear end walls, a clamp formed of resilient metal disposed vertically in said socket and having a foot at its lower end and inner and outer arms extending upwardly from the foot, the outer arm being disposed flat against an end wall of said socket and the inner arm being curved longitudinally and having its upper end protruding from the socket, and a thumb screw threaded through aligned openings formed through the said end wall of the socket and the outer arm and having its inner end abutting the inner arm and constituting means for forcing the inner arm into gripping engagement with a wheel fitted into the socket through the open upper end thereof.

2. An attachment for a wheeled vehicle comprising a ski, a wheel-receiving socket carried by and projecting upwardly from said ski and open at its top and having side walls and front and rear end walls, a clamp formed of resilient metal disposed vertically in said socket adjacent an end wall thereof and having an arm free at its upper end and biased towards the said end wall of the socket and curved longitudinally for fitting about the periphery of a wheel fitted into the socket through the upper end thereof, and a thumb screw threaded through an opening in the rear wall and engaging the said arm of the clamp to force the said arm to a gripping position.

3. An attachment for a wheeled vehicle comprising skis spaced transversely from each other, sockets projecting upwardly from said skis and open at their tops and having inner and outer side walls and front and rear walls, the side walls having upper edge portions formed with opposed recesses of dimensions adapting them to receive hubs of wheels fitted into the sockets through the open tops thereof, ears extending laterally from the inner side walls of said sockets, rods extending between said sockets and having ends formed with eyes, bolts passed through the eyes and said ears and securing the rods to the ears, the other ends of the rods being threaded, and a turnbuckle connecting the threaded ends of said rods.

"E" LEE RAE CLARK.
